Application June 14, 1937, Serial No. 148,132

5 Claims. (Cl. 155—24)

This invention relates to a chair and in particular to a chair mounted upon a spring base.

An object of this invention is to provide a spring base wherein the effective length of the spring is automatically shortened as the weight on the chair increases.

Another object of this invention is to provide a guide for the curved portion of a spring member, wherein the curvature of the guide is less than the curvature of the spring, so that as the tension is increased on the spring the effective length of the spring is shortened to thereby decrease the resiliency thereof.

Another object of this invention is to provide a chair wherein the rocking movement is limited.

Another object of this invention is to provide a chair wherein parts are made from two types of metal, one superimposed upon the other for the purposes of ornamentation.

Another object of this invention is to provide resiliently mounted rigid uprights for supporting the chair.

Another object of this invention is to provide limits for the rocking movement of the chair.

Another object of this invention is to provide a free limited movement for the chair and to provide a stop for the movement.

Another object of this invention is to provide a chair that is quickly and easily constructed, but at the same time is strong, dependable, efficient and pleasing in appearance.

Other objects and advantages reside in the construction of parts, the combination thereof and the mode of operation, as will become more apparent from the following description.

Fig. 1 shows a perspective view of the chair.

Fig. 2 is a side elevation.

Fig. 3 is another side elevation with the back and arm rests folded.

Figs. 4, 5 and 6 show detail enlarged fragmentary views of the operation of the spring that has been designed to automatically change the resiliency thereof as the weight on the chair changes.

Fig. 7 is a fragmentary sectional view.

Fig. 8 is a fragmentary sectional view taken on the line 8—8 of Fig. 9.

Fig. 9 is a fragmentary sectional view taken on the line 9—9 of Fig. 8.

Fig. 10 is another fragmentary sectional view.

Figs. 4, 5, 6, 8, 9 and 10 have been drawn to a larger scale than that of the other above views.

Fig. 11 is another modification disclosing a fragmentary view of a resilient support for the chair.

Fig. 12 is a sectional view taken substantially on the section line 12—12 of Fig. 11.

Fig. 13 discloses another modification wherein the snubber has been used to provide resiliency.

Fig. 14 is another modification similar to Fig. 13, wherein a pair of snubbers has been disclosed.

Fig. 15 is another modification disclosing a snubber seated in a cavity limiting the expansion of the snubber.

For the sake of clearness, the canvas or fabric upholstery has not been shown in Figures 2, 3, 4, 5, 6 and 7. In other words, these modifications have been shown before the upholstery has been put into position.

Numerous attempts have been made to make chairs utilizing a pair of spring members for supporting the seat in spaced relation with respect to the base. Such chairs have found a ready outlet on the market. They are cheap, they are efficient and quite satisfactory. In at least some of these there are some objections, one of which is the absence of any adjustments compensating for different weights on the chair, that is, the stiffness of the springs remains the same irrespective of the weight, neglecting, of course, the inherent characteristic of all springs to offer resistance wherein the deflection of the spring varies as the force applied. In the modification disclosed herein the effective length of the spring is automatically shortened as the weight increases, as will appear more fully later.

The seat portion 10 of the chair is supported on a pair of spring members 12 mounted upon a base 14. The seat portion 10 includes a pair of frame members 16 supporting a canvas 18, or any other suitable material. The side frame members 16 are held in fixed spaced relation by a reinforcing member 20 and a tie rod 22.

A back rest including a pair of vertically sloping members 24 is pivotally mounted upon the side frame members 16. A suitable canvas or other back rest 26 spans the distance between the vertically sloping side members 24. These side members are held in fixed spaced relation by a curved brace 28 and a tie rod 30. Near the base of the side members 24 is fixedly attached a metallic clasp 32 screwed or riveted to the side members 24. A rod or pintle 36 is passed through the bight of the clasp 32 and engages a U-shaped clevis member 38 passing around the side member 16. This provides a pivotal support for the back rest.

The chair is also provided with side arms including a horizontal member 40 pivotally mounted at 42 to the vertically sloping side member 24.

and pivotally mounted at 44 to a suitable bell crank bracket 46 fixedly attached by a pair of screws or rivets 48 to a vertically disposed arm rest supporting member 50 pivotally mounted at 52 to the side frame member 16. This permits orientation or rotation of the back rest forwardly, so as to fold in juxtaposed relation over the seat portion 18 for the purposes of saving space when shipping, moving, storing, handling and the like. 10 The seat and back portion, as already stated, is mounted upon a pair of spring members 12 fixedly mounted upon a base 14, including a pair of side members 60 held in fixed spaced relation by a pair of rungs 62 and adapted to engage the 15 floor for a considerable distance along the length of the side members 16.

The side members 16 of the seat have been provided with a notch for receiving the upper end 64 of the spring 12. The forward end of the side member 16 has been curved in close proximity to the curvature of the spring 12; but the radius of curvature of the side member 16 is less than the radius of curvature of the spring member 12. 20

The seat portion is suspended and the weight 25 carried by a suitable rivet or bolt 70 passing through the end of the spring member 12 and the side member 16. This retaining pin has been mounted a very short distance ahead of the point of the center of gravity when the chair is used 30 in a normal manner. This permits the suspension of the weight carried by the side seat member near the center thereof and near the center of gravity. The pin 70 being placed a short distance ahead of the center of gravity causes the 35 side member to fulcrum about this point, so as to have a tendency to raise the forward end 72 of the side member 16 against the forwardly extending portion of the spring 12.

The bottoms of side members 60 have also been 40 provided with notches oppositely disposed with the notches provided in the side members 16. These notches provide a clearance adjacent to the floor for accommodating the rearwardly extending ends of the springs. Again, the notches terminate a short distance ahead of the center of gravity of the weight on the chair. The lower 45 ends of the springs are held in position by a suitable rivet or bolt 80, passing through the rear end of the spring member 12 and through the side member 60, so that the retaining pin 80 functions as a fulcrum having practically half of the side member 60 serving as a lever of the first class engaging the loop or the bend of the spring. The radius of curvature of the side members 60 is less 50 than the radius of curvature of the spring.

This structure causes the effective length of the resilient portion that is utilized to be shortened as the weight on the chair is increased. If the chair is occupied by a light weight person, the effective length of the spring is substantially equal to the distance between the notches, that is, the spring will come in contact with the end 72 at 84 as seen in Fig. 4. If the chair is occupied by a person of medium weight, the spring will close against the end 72, coming in contact at 86 as shown in Fig. 5. If the chair is occupied by a heavy person, the spring will come in contact with the nose 88 of the end 72, that is, as far as member 16 is concerned.

A similar shifting will take place between the curvature of the bottom member 60 and the lower end of the spring, that is, with a light weight person, the effective length of the spring will be the entire length of the bight, that is, 75 from one leg to the other. When a medium

weight person occupies the chair, the effective length will be from the sudden break 86 of member 16 to the corresponding sudden break of member 60. Then the effective length of the spring is somewhat shorter than when the chair is occupied by a light weight person; but not as short as when the chair is occupied by a heavy weight person, when the effective length is the distance between members 16 and 60.

This shifting of the effective length of the 10 spring changes the resiliency or the ease of the chair. For a comparatively light person the spring 12 is easily flexed. For a heavy person the spring is comparatively rigid—properly so. For a medium weight person the resiliency of the spring 15 is greater than for a heavy weight person and less than for a light weight person. Although three points have been described, or three degrees of resiliency have been discussed by properly selecting the curvature of the spring and of the guide 20 portions, any number of effective variations may be obtained.

As the center of gravity of a normal load is substantially along the direction of the arrow A shown in Fig. 2, it can be readily seen that member 16 functions as a lever of the first class fulcrumed at the rivet 70, the extreme end 72 of member 16 being forced up against the leg of the U-shaped spring member 12. In the event the center of gravity of the load on the chair should be shifted towards the forward edge thereof, there would be a tendency for the seat to rotate in a clockwise direction, as viewed in Fig. 2, that is, there would be a strain on the rivet 70. In order to avoid this, a U-shaped clamping member 90 may be passed around the end 72 of member 16 and the spring, so as to prevent rotation of the seat portion in a clockwise direction, as viewed in Fig. 2. Instead of a clamp or band being passed around the forward end of 72, a suitable screw, bolt or rivet could be used. However, such an arrangement would have a tendency to weaken the spring when near the bend, which is objectionable. Therefore, a clamp, or strap, or band is preferable. A similar arrangement could be used in connection with the forward end of member 60 and the lower leg of the U-shaped spring 12.

In the modification disclosed in Fig. 11, instead of a wooden base member as disclosed in Fig. 1, a metal member 100, is provided, which member extends substantially parallel to the floor. Member 100 has near the forward end a downwardly deflected portion 102 terminating in a horizontal portion 104 supported in close proximity to the floor upon a rubber sleeve 106 completely enclosing this portion. The forward end member 100 is bent to form an eye 108.

Instead of a resilient upright member 12, as disclosed in Fig. 1, a channel shaped upright member 110 is used. This member is provided with the flanges 112 giving rigidity to the member 110. A bar having a T-shaped cross sectional area could be used instead of the channel bar. The lower face of member 110, as disclosed in Fig. 12, is provided with a depression in which is mounted a strip of chromium plated metal 114, for the purposes of ornamentation. It can be readily seen that if member 110 is painted a suitable contrasting color, as for example black, the chromium plated strip 114 will greatly enhance the appearance of the chair.

The rearward end of member 110 is nested under a bracket 116, having a pair of downwardly projecting ears 120. The rear ends of member 75

110 and of the bracket 116 are held in fixed relation by a suitable rivet 118. A pin 122 passes through suitable apertures in the ears 120 and the eye formed by the end 108 of member 100.

5 Thus, it is seen that the ears 120 of bracket 116 cooperate with the forward end of member 100 to form a hinge or a pivot for member 110.

A rubber snubber 124 is mounted underneath the rearward end of member 110 and seated upon 10 the horizontal portion 104 of member 100. This snubber 124 permits a yielding movement or a cushioning, so that the chair may oscillate or rock about the pivot 122. The rubber sleeve 116 completely houses the juncture or the joint between 15 members 100 and 110, so that 100 and 110 have the appearance of being a continuous member mounted upon a very heavy snubber, which is merely a casing or a housing for the joint.

In the modification disclosed in Fig. 13, the 20 horizontal member 130 extends along the floor and supports the chair. The forward end of member 130 is enclosed in a metallic rectangular sleeve 132 held in position by suitable screws or rivets 134 and is provided with a loop 136, constituting the forward end of the base.

An upright supporting member 138 has been disclosed as supporting the seat of the chair. This member 138 is pivotally mounted at 140 to the loop 136. The forward end of member 130 is 30 arranged in spaced relation with respect to the rear edge of member 138. This space between the forward end of member 130 and the rear edge of member 138 supports a snubber 142, limiting the rearward movement of member 138 about the 35 pivot 140. This permits of a rocking movement of the chair supported on member 138. In this connection reference has been made to the chair being supported on a member 138. As a matter of fact, the chair is supported on a pair of these 40 members 138 in spaced relation much the same as the disclosure in Fig. 1, excepting the uprights 138 do not yield per se.

In the modification disclosed in Fig. 14 the 45 upright 138 has been pivoted at 144. The loop 136 extends beyond the forward edge of 138 so as to provide pockets both at the front and the rear of 138 supporting suitable snubbers 142. In this modification the swinging movement of member 138 may be somewhat greater than that 50 disclosed in Fig. 13.

In the modification disclosed in Fig. 15 the 55 upright 138 is arranged in substantially flush relation with respect to the horizontal base member 130. The rear edge of member 138 is provided with a cavity 150 in which is seated a rubber snubber 152. It is to be noted that a clearance 154 is provided along each edge of the snubber 152. This provides a space for the expansion of the rubber, which space is limited, 60 so that as the upright swings about the pivot 140 rearwardly, the snubber 152 will eventually fill the cavity 150 at which time the rearward movement of the upright 130 is stopped.

Although the preferred modification of the 65 vice has been described, it will be understood that within the purview of this invention various changes may be made in the form, details, proportion and arrangement of parts which generally stated, consist in a device capable of carrying 70 out the objects set forth, in the novel parts, combination of parts and mode of operation, as disclosed and defined in the appended claims.

Having thus described my invention, I claim:

1. In a device of the character described a U-shaped leaf spring member, a pair of substantially parallel members contacting each a leg of the U-shaped member and extending towards the bight of the U-shaped member, the 5 ends of the parallel members being curved so as to have a radius of curvature less than the radius of curvature of the U-shaped member and means for securing the ends of the legs of the U-shaped members to the parallel members, so that as the 10 load is applied to the parallel members beyond the ends of the legs of the U-shaped members the curved portion of the parallel members engages the bight of the U so as to decrease the 15 effective length of the resilient portion as the force increases to thereby automatically stiffen the spring member as the load increases.

2. A spring supported chair including a base portion, a seat portion and a U-shaped leaf spring member for holding the seat portion in 20 spaced relation from the base portion, one leg of the U-shaped member being fixedly attached to the base portion, said seat portion including a longitudinal underslung frame member extending into the U-shaped member on the under side 25 of the upper leg, means for fixedly attaching the side member to the end of the upper leg, said means being located a short distance in front of the center of gravity of a normal load applied to the chair so as to cause the longitudinal 30 member to function as a lever of the first class fulcrumed upon said fastening means.

3. A spring supported chair including a base portion, a seat portion and a U-shaped leaf spring, the seat portion including a member hung 35 in underslung relation with respect to the upper leg of the U-shaped member, the lower leg of the U-shaped member being suspended in underslung relation with respect to the base portion to thereby utilize the maximum effective length 40 of the bight of the U-shaped spring member.

4. A spring supported chair including a base portion, a seat portion and a U-shaped leaf spring member for holding the seat portion in spaced relation with respect to the base portion, 45 said seat portion including an arcuate guide extending on the under side of the upper leg of the U-shaped leaf spring member so as to have the arcuate guide portion in engagement with the concave side of the curvature of the U-shaped 50 leaf spring member and the base portion having an arcuate guide portion mounted above the lower leg of said U-shaped leaf spring member, so that the second arcuate guide portion is in engagement with the concave side of the lower 55 curvature of the U-shaped leaf spring member for automatically shortening the effective resilient portion of the U-shaped leaf spring member as the weight on the seat increases.

5. A spring supported chair including a base portion and a seat portion, a U-shaped leaf spring, and a pair of arcuate guide means extending along the legs of the U-shaped leaf spring and engaging the concave side of the bight of the U-shaped leaf spring, the arcuate guide 65 means having the radius of curvatures less than the radius of curvature of the U-shaped leaf spring, said guide means being mounted so that the guide portions are utilized to reduce the effective length of the bight of the U-shaped leaf 70 spring as the weight is increased on the chair.

LOUIS J. ZERBEE.
